United States Patent Office

Des. 230,256
Patented Feb. 5, 1974

230,256

BEVERAGE BOTTLE

John L. Ckola, 3833 Jewell St.,
San Diego, Calif. 92109

Filed May 2, 1972, Ser. No. 249,754

Term of patent 3½ years

Int. Cl. D9—²*

U.S. Cl. D9—102

FIG. 2

FIG. 1

FIG. 1 is an elevational view of a beverage bottle showing my new design; and

FIG. 2 is a top plan view thereof.

The side opposite that seen in FIG. 1 is the same in appearance as the side shown.

I claim:

The ornamental design for a beverage bottle, as shown and described.
